(57) **CLAIM**

The ornamental design for a packaged apparatus for injecting fluid in air conditioning or refrigeration systems, as shown and described.

DESCRIPTION

FIG. 1 is a front perspective view of a packaged apparatus for injecting fluid in air conditioning or refrigeration systems showing our new design;

FIG. 2 is a front view thereof;

FIG. 3 is a rear view thereof;

FIG. 4 is a right side view thereof;

FIG. 5 is a left side view thereof;

FIG. 6 is a bottom view thereof; and,

FIG. 7 is a top view thereof.
